US0D1004356S

(12) **United States Design Patent** (10) **Patent No.:** **US D1,004,356 S**
(45) **Date of Patent:** **** Nov. 14, 2023**

(54) **GAS STOVE**

- (71) Applicant: **SENGOKU WORKS, LTD.**, Kasai (JP)
- (72) Inventors: **Tadashi Sengoku**, Kasai (JP); **Takehira Sengoku**, Kasai (JP); **Akihiko Shirota**, Kasai (JP)
- (73) Assignee: **SENGOKU WORKS, LTD.**, Kasai (JP)
- (**) Term: **15 Years**
- (21) Appl. No.: **29/823,678**
- (22) Filed: **Jan. 19, 2022**

(30) **Foreign Application Priority Data**

- Aug. 13, 2021 (JP) ..... 2021-017492 D
- (51) **LOC (14) Cl.** **07-02**
- (52) **U.S. Cl.**
USPC **D7/337; D7/346**
- (58) **Field of Classification Search**

(57) **CLAIM**

The ornamental design for a gas stove, as shown and described.

DESCRIPTION

- FIG. 1 is a front view;
FIG. 2 is a rear view;
FIG. 3 is a right side view;
FIG. 4 is a left side view;
FIG. 5 is a top view;
FIG. 6 is a bottom view;
FIG. 7 is a perspective view;
FIG. 8 is a perspective view with a cover covering the burner parts and a trivet in open state;
FIG. 9 is a perspective view with the cover and a right side part in open state; and,
FIG. 10 is a perspective view with the cover in open state and a pipe pulled out.

1 Claim, 5 Drawing Sheets
